SLIT SCARF

Vera Neumann, Ossining, N. Y.

Application August 30, 1950, Serial No. 11,991

Term of patent 14 years

(Cl. D3—12)

To all whom it may concern:

Be it known that I, Vera Neumann, a citizen of the United States, residing in Ossining, Westchester County, State of New York, have invented a new, original, and ornamental Design for a Slit Scarf, of which the following is a specification, reference being had to the accompanying drawing, constituting a part hereof, showing a plan view of a slit scarf illustrating my new design. The reverse side is similar to the obverse.

This application is a continuation-in-part of my application Design Serial No. D. 4,905, filed September 8, 1949, now abandoned.

I claim:

The ornamental design for a slit scarf, substantially as shown and described.

VERA NEUMANN.
